UNITED STATES PATENT OFFICE.

BARNY S. STEINFELD, OF NEW HAVEN, CONNECTICUT, ASSIGNOR OF
ONE-HALF TO LOUIS MAASS, OF SAME PLACE.

COIN-CONTROLLED LUNG-TESTER.

SPECIFICATION forming part of Letters Patent No. 635,607, dated October 24, 1899.

Application filed January 3, 1899. Serial No. 700,880. (No model.)

To all whom it may concern:

Be it known that I, BARNY S. STEINFELD, of New Haven, in the county of New Haven and State of Connecticut, have invented a new Improvement in Coin-Controlled Lung-Testers; and I do hereby declare the following, when taken in connection with the accompanying drawings and the letters of reference marked thereon, to be a full, clear, and exact description of the same, and which said drawings constitute part of this specification, and represent, in—

Figure 1, a face view of a coin-controlled lung-tester constructed in accordance with my invention; Fig. 2, a broken perspective view of the operating mechanism; Fig. 3, a sectional view of the coin-releasing device; Fig. 4, a broken sectional view of the lower end of the cylinder and piston.

This invention relates to an improvement in coin-controlled lung-testers, and particularly to that kind in which the mechanism is released or placed in condition for operation by the weight of a coin, the object of the invention being a simple device which is normally out of position for operation, but which is opened and adapted for operation by the weight of a coin and simple means for releasing the coin after it has once performed the function of placing the mechanism in condition for operation; and it consists in the construction as hereinafter described, and particularly recited in the claims.

The case A may be of any approved shape or construction, having a dial B and coin-slot C. Within the case is mounted a cylinder D, closed at its upper end and provided at its top and bottom with flanges a b, which set over vertical rods d, which are mounted in the case, and which at their upper ends support an inverted-cup-shaped cap e. Within the cylinder is a piston the rod E of which is provided at its lower end with arms f, which are secured to suitable posts g, whereby the piston is held in a vertical position. This piston is hollow, and its end extends through a transverse partition F. On one side of the cylinder D is a rack G, and mounted in the case in position to mesh therewith is a pinion H on a shaft I, said shaft extending outward through the case and carrying a pointer J,

adapted to sweep the dial B. Also mounted on the shaft I is a ratchet-wheel K, and mounted on a post L, which also forms a support for the shaft I, is a pawl M. One end m of this pawl engages with the ratchet K, so as to hold it against rotation in one direction, while the other end projects outward in position for engagement with the inner end of a lever N, which is pivoted to an arm N', secured to the post L, and which projects outward through the side of the case, beyond which it is formed with a yoke N², to receive the mouthpiece O of an inlet-pipe O', which will be hereinafter described, the weight of the pipe and mouthpiece being sufficient to depress the lever N and lift the arm m' of the pawl, so as to throw the point m out of engagement with the ratchet K, said pawl being normally held in position to engage the ratchet by a spring m². Suitably mounted in the case is a valve P, having a stem P', with which the pipe O' is connected. This valve opens into a tube Q, the passage thereto being opened or closed by a plug R, to which plug is secured a coin-lever S, provided at one end with a weight S' and at its opposite end with coin-receiving fingers S², which are normally in position just below the inner end of a chute C', which extends from the slot C in the case, and so that the weight of a coin at the finger end of the lever is sufficient to turn the plug R and open the valve. In addition to the counterbalancing-weight S' at one end of the lever S, I preferably provide a spring S³, the tendency of which is to lift the coin end of the lever and so assist in closing the valve. The tube Q leads to a coin-releasing device, which consists of a cylinder T, in the under side of which are two ports t t', opening into a pipe U, which is connected with the valve-stem E. Within the cylinder is a tubular slide V, closed at its inner end, from which an arm V' extends through the end of the cylinder T. In this slide is an opening V² in position to register with the ports t t' when the slide is moved inward. This slide is normally forced rearward by a spring W, arranged within the cylinder between its inner end and the inner end of the slide. The arm V' stands in line with the inner end of the coin-lever S and so as

to strike the edge of a coin X when the same shall have depressed the end of the lever S. Preferably I arrange a spring h between the disk E and the upper end of the cylinder D, the tendency of which is to force the cylinder downward.

The operation of the device is as follows: A coin being dropped through the slot C will descend through the chute C' into the fingers 10 S² and depress the lever S and so as to turn the plug R to open the valve P. The tube O' is removed from engagement with the yoke N² of the lever N, which under the action of the spring m² is lifted by the engagement of 15 the end m' of the pawl bearing upon its inner end, this movement of the pawl throwing the inner end m into engagement with the ratchet-wheel K, so as to prevent its rotation in one direction. The valve P being 20 opened, a person can blow through the tube O', the air passing through the valve into the tube Q and from thence to the cylinder T. The first pressure of the exhalation of air forces the slide T inward and so as to project 25 the arm V' into engagement with the edge of the coin in the holder and force it out of the fingers S² into a suitable receptacle. After thus forcing the coin out of the fingers the end of the arm comes in contact with the fingers and so prevents the lever S from rising. 30 The inward movement of the slide V brings the opening V² into registration with the ports t t' and permits the air to pass downward through the tube U and through the piston-stem E into the cylinder D and so as to lift 35 the cylinder. This upward movement of the cylinder with its rack G rotates the pinion H, and hence rotates the shaft I and turns the pointer J. The pawl m, being in engagement 40 with the ratchet K, prevents the return movement of the shaft I. The moment the pressure of air ceases the release of pressure in the slide T permits the spring W to react to force the slide to its normal position and 45 so close the port t, at the same time withdrawing the arm V' and releasing the lever S, which under the action of its counterbalancing-weight S' and the spring S³ will turn the plug R so as to close the valve P. This again 50 places the machine out of condition for operation until another coin is inserted. Before again operating the machine the lever N should be depressed either by placing the mouthpiece O in the yoke N² or by depressing 55 it by hand and so as to lift the inner end of the lever to turn the pawl M and throw its point m out of engagement with the ratchet K, whereby the shaft I is free to rotate in the opposite direction. This shaft being released, 60 the weight of the cylinder D, assisted by the action of the spring h, will cause it to descend to its normal position and turn the pointer to the zero point and ready to register for a second operation. It will thus be seen that as 65 soon as the pressure is relieved after once starting it the device is thrown out of condition for further movement, so that but one

exhalation can be registered, for the moment pressure is relieved the valve will be closed. As the tube V withdraws the closed end passes 70 beyond the port t', so as to permit the air in the pipe U to escape through the outer end of the cylinder around the arm V'.

It is evident that in constructing my improved device certain changes in the arrangement of parts may be made, and I therefore do not wish to be understood as limiting my invention to the exact construction shown, but hold myself at liberty to make such changes as fall within the scope of my invention. 75 80

Having fully described my invention, what I claim as new, and desire to secure by Letters Patent, is—

1. In a coin-controlled apparatus, the combination with a vertically-movable cylinder, of a fixed hollow piston projecting thereinto, a rack on said cylinder, an indicating pointer-shaft having a pinion in mesh with said rack, a tube opening through the piston into said cylinder, and a coin-controlled valve for opening and closing the passage for air thereto, substantially as described. 85 90

2. In a coin-controlled apparatus, the combination with a vertically-arranged fixed piston, of a vertically-movable cylinder thereon, a rack on one side of the said cylinder, a pointer-shaft having a pinion in mesh with said rack, a ratchet-wheel also mounted on said shaft, a pawl mounted for engagement 100 with said ratchet, a lever projecting outward through the case, and adapted at its inner end for moving said pawl, a tube opening through the piston into the cylinder, and a coin-controlled valve adapted to open or close the passage thereto, substantially as described. 105

3. In a coin-controlled apparatus, the combination with a fixed piston, of a vertically-movable cylinder thereon, pipes for the passage of air thereto, a valve in said passage, 110 the plug of which is connected with a coin-operated lever, and means operated by the passage of air for throwing the coin out of engagement with said lever, substantially as described. 115

4. In a coin-controlled apparatus, the combination with a fixed piston and vertically-movable cylinder thereon, air-passage tubes opening into said cylinder, a coin-controlled valve for opening and closing the passage through said tubes, and a coin-releasing device consisting of a cylinder and a slide therein normally closing the passage through said tubes and having an opening for clearing said passage, and an arm carried by said slide and projecting through said cylinder into line with the coin when the coin-lever is in its depressed position, substantially as described. 120 125

5. In a coin-controlled apparatus, a coin-releasing device comprising a cylinder and a slide therein having an arm projecting from its inner end through the cylinder, a coin-lever having its coin-retaining end adapted to be depressed by the weight of a coin into line 130

with said arm, which is adapted to be forced outward, whereby the coin is thrown from the coin - operated lever, substantially as described.

- 5 6. In a coin-controlled lung-tester, the combination with an indicator, of means for moving the same, including a tube, a valve in said tube, a rotatable plug in said valve, and a lever secured to said plug and provided at 10 one end with coin-receiving fingers, whereby

the weight of the coin depresses said lever to open said valve, substantially as described.

In testimony whereof I have signed this specification in the presence of two subscribing witnesses.

BARNY S. STEINFELD.
